UNITED STATES PATENT OFFICE.

DANIEL B. WESSON AND JOSEPH H. WESSON, OF SPRINGFIELD, MASSACHUSETTS.

DESIGN FOR A PISTOL-CHEEK.

SPECIFICATION forming part of Design No. 21,823, dated August 30, 1892.

Application filed April 2, 1892. Serial No. 427,547. Term of patent 14 years.

To all whom it may concern:

Be it known that we, DANIEL B. WESSON and JOSEPH H. WESSON, of Springfield, in the county of Hampden and State of Massachusetts, have invented and produced a new and original Design for a Cheek-Piece for a Pistol-Grip, of which the following is a specification, reference being had to the accompanying drawings, forming part thereof.

10 Figure 1 is an edge view of the cheek-piece. Fig. 2 is an outer face view thereof. Figs. 3 and 4 are respectively a front and rear end view of the cheek-piece.

The letter *a* designates the outer face of the cheek-piece; *b*, the inner face; *c*, the front end, and *d* the rear end thereof. Said outer face *a* is formed upon a regular curve from the upper to the lower edge of the cheek-piece transversely of the latter, as shown in 15 Figs. 3 and 4, while longitudinally of the cheek-piece it commences at the rear end of the latter with a regular curve, extending from the inner face *b* to the point marked 1, and thence extends to the point marked 2 20 Figs. 3 and 4, while longitudinally of the cheek-piece it commences at the rear end of the latter with a regular curve, extending from the inner face *b* to the point marked 1, and thence extends to the point marked 2 25 (see Fig. 1) by a substantially straight line, which gradually approaches said inner face.

At the point marked 2 it merges into the substantially circular panel *e*, which panel is slightly concaved longitudinally of the cheek-

30 piece, as shown. The cheek-piece terminates at its front end in the curved boundary-line of the panel *e*, and two straight lines 33 joining said curved line to the upper and lower edge lines, respectively. At its rear end it 35 terminates in a straightline extending trans-

versely across the cheek-piece and joining the upper and lower edge lines by regular curves, as shown in Fig. 2. The upper and lower edge lines of the cheek-piece are formed upon irregular curves, which correspond substantially with each other, the former projecting slightly beyond the latter at the front end of the cheek-piece, as shown. A sunken or grooved line 4 within the outer face *a* extends continuously from a point substantially midway between the ends of one of the straight portions 3 at the front end of the cheek-piece to a similar point in the other straight portion 3, said line lying adjacent to and parallel with the upper and lower edge lines and rear 40 end line of the cheek-piece, as shown in Fig. 2. Said sunken or grooved line 4 gives a distinctive and pleasing appearance to the outer face of the cheek-piece and constitutes the leading feature of our design. The distance 45 between said line and the edges of the cheek-piece can be varied within reasonable limits without impairing the unity of our design.

Having thus fully described our design, what we claim, and desire to secure by Letters Patent, is—

The design for the cheek-piece of a pistol-grip, substantially as herein shown and described.

DANIEL B. WESSON.
JOSEPH H. WESSON.
